UNITED STATES PATENT OFFICE

ARTHUR R. WEIS, OF HUNTINGTON PARK, CALIFORNIA, ASSIGNOR OF ONE-HALF TO PACIFIC PUMP WORKS, OF HUNTINGTON PARK, CALIFORNIA, A CORPORATION OF CALIFORNIA, AND ONE-HALF TO GEORGE E. BIGELOW, OF HUNTINGTON PARK, CALIFORNIA

INTERMEDIATE BEARING CONSTRUCTION

Application filed November 8, 1929. Serial No. 405,624.

My invention relates to bearings, and more particularly to a novel bearing construction which finds a particular utility in combination with a deep-well turbine pump.

Ordinary turbine pumps provide a pump unit positioned in a well, the impellers of which are driven by a line shaft extending upward to the surface of the ground. The number of impellers necessary depends, for one thing, upon the distance it is necessary for the pump to lift the well fluid, and in the deeper installations it has been found advisable when using a large number of impellers to utilize an intermediate bearing situated substantially midway between the upper and lower impellers. It is in this capacity that I will particularly describe my invention, though it should be clear that I am not limited to this use neither in so far as the turbine pump is concerned nor in so far as an intermediate bearing therein is concerned.

It is an object of my invention to provide a bearing structure through which a stream of fluid is permitted to pass, this fluid being filtered through a novel filtering means to remove therefrom any abrasive particles.

A further object of my invention is to design the fluid passage of a pump unit in such a manner that this flow of well fluid takes place through the bearing in a given direction.

This invention includes as one of its more detailed objects the provision of an upward flow through the bearing, the velocity of this flow being sufficiently low so that any foreign particles entrained in the liquid will not be carried upward by this flow, but will settle therefrom.

A further object of the invention is to provide a novel means of protecting the upper end of the bearing chamber from the entrance of grit or other foreign particles which may be carried by the well fluid.

Further objects of my invention will be made evident hereinafter.

In the drawing,—

Fig. 1 is a utility view of the turbine pump incorporating my invention in the intermediate bearing thereof.

Fig. 2 is a medial sectional view of the intermediate bearing of Fig. 1.

Fig. 3 is a sectional view taken on the line 3—3 of Fig. 2.

Fig. 4 is a sectional view taken on the line 4—4 of Fig. 2.

As best illustrated in Fig. 1, one use of my invention is in the deep-well turbine art wherein a casing 10 is set in a well 11 and surrounds a discharge pipe 12 which extends downward from a pump head 13 at the surface of the ground and supports a pump unit 14 at the lower end thereof. This pump unit comprises upper and lower series of pump bowls 15 and 16 joined by an intermediate bearing structure 17, the lower series supporting a lower bearing structure 18 and a suitable strainer 19 through which well fluid is drawn by means of a series of impellers mounted on a line shaft which extends upward to the pump head 13 and is rotated by a suitable prime mover 20.

The constructional details of the invention are best illustrated in Fig. 2 wherein I have illustrated an upper bowl 24 including an impeller chamber 25 in which an impeller 26 is adapted to rotate, this impeller being suitably secured to the line shaft previously mentioned and designated in Fig. 2 by the numeral 27. Similarly, I have illustrated a lower pump bowl 30 providing an impeller chamber 31 in which an impeller 32 similar to the impeller 26 is located, this impeller being also secured to the shaft 27 which passes downward through the intermediate bearing structure 17. I have illustrated this bearing structure as being threadedly secured to the upper and lower bowls 24 and 30, but any suitable means of connection may be used.

When the impellers are rotated well fluid

is drawn upward through the impeller 32 and is forced through one or more bowl passages 34 formed between a shell 35 thereof and a dome member 36 supported by webs 37 in the usual manner. This fluid then rises through one or more fluid passages 40 formed through the bearing structure 17 and defined between a casing 41 thereof and a hub portion 42 supported therein as by webs 43. At this point the fluid is forced upward into the upper impeller 26 and thus upward to the discharge pipe 12 through which it rises to the surface of the ground.

The hub 42 provides a bore 45 which is only slightly larger in diameter than the shaft 27, the upper end of this hub being counterbored to form a bearing chamber 46 in which is positioned a bearing 47 which is preferably of the sleeve type and which may be formed of any suitable bearing material, such as babbitt or bronze, or which may be formed of a substance which is lubricated by the well fluid being pumped such as lignum-vitæ.

25 The upper end of the bearing chamber is filled with a packing 49 on which a pair of rings 50 rests. Secured to the shaft above these rings as by a set screw 53 is a deflector 54 which provides a skirt 55 extending downward over a reduced diameter portion 56 of the hub 42 so as to provide a longitudinal channel 57 therebetween. The lower end of the skirt 55 stops short of a shoulder 58 so as to provide an annular space 59 which is 35 in communication with the fluid passing through the fluid passages 40.

The lower end of the bore 45 is counterbored as indicated by the numeral 60 so as to retain an insert member 61. Through this 40 member is bored a hole which is slightly larger in diameter than the diameter of the shaft 27 so as to provide an opening 63 therebetween which communicates with the lower end of the bearing 47. The lower end of this 45 opening communicates with the bowl passage 34 through an annular passage 65 formed between the lower end of the insert member 61 and the upper end of the dome member 36. This annular passage prefer- 50 ably extends radially outward from the axis of the shaft, and the width thereof is relatively small, being in the neighborhood of several thousandths of an inch.

The fluid passages in the lower pump bowl 55 30 and the bearing structure 17 are so designed that the pressure of the fluid therein at a point opposite the annular passage 65 is larger than the fluid pressure opposite the annular opening 59. This may most easily 60 be accomplished by suitably proportioning the cross-sectional areas of these passages so that the well fluid opposite the annular passage 65 is moving slower than the well fluid passing the annular opening 59. The lower 65 end of the bearing chamber is thus subjected

to the pressure existing at a primary section, this pressure being higher than that to which the upper end of the bearing chamber is subjected at a secondary section. This differential pressure is usually very low, usually being in the neighborhood of slightly more than one pound per square inch.

70 Such a differential pressure sets up an upward flow of well fluid through the bearing 46 which parallels the flow through the fluid passage 40, the former flow taking place through the annular passage 65 and rising through the opening 63 and being discharged through the longitudinal passage 57 after 75 passing adjacent the journaling surfaces of the bearing 47 and the packing 49. The annular passage 65 acts to strain the well fluid passing therethrough so that substantially no abrasive particles can reach the bearing chamber 46 and thus destroy or injure the bearing surfaces. However, even if abrasive particles have already passed the annular passage 65, no harm would result for the packing 49 limits the flow through the bearing to such an extent that the velocity thereof is too low 80 to carry the abrasive particles upward therewith, these particles settling therefrom and being thus prevented from reaching the journaling surfaces. The deflector 54 acts to prevent the entrance into the bearing chamber 85 46 of any abrasive particles which may settle from the well fluid rising through the fluid passages thereabove, these particles being thrown outward by centrifugal force when they come in contact with the periphery of 90 this deflector.

While I have described the differential pressure as being set up by suitable design of the cross-sectional areas of the fluid passages, it should be clear that other means 105 for accomplishing this end may be utilized without departing from the spirit of my invention. Furthermore, while I have found an upward flow to be especially desirable, it is within the scope of this invention to provide a differential pressure whereby a downward flow takes place through the bearing, this flow being suitably strained as by the longitudinal passage 57 to remove therefrom all abrasive particles.

110 Finally, it should be noted that the walls of the annular passage 65 are stationary so that no material wear takes place which would tend to increase the width of this passage and thus allow abrasive particles to pass 115 therethrough.

I claim as my invention:

1. In combination: a bearing construction 120 providing a tapering fluid passage therethrough so designed that the fluid pressure at a primary point is higher than the fluid pressure at a secondary point therein; a bearing mounted in said bearing construction, said bearing resting in a bearing chamber 125 communicating with said fluid passage 130

at said primary and secondary points; a shaft journalled in said bearing; means operatively connected to said shaft for forcing fluid through said fluid passage, a small portion of said fluid passing through said bearing; and means at said primary point for straining said small portion of said fluid before it reaches said bearing.

2. In combination: a bearing construction providing a tapering fluid passage therethrough so designed that the fluid pressure at a primary point is higher than the fluid pressure at a secondary point therein; a bearing mounted in said bearing construction, said bearing resting in a bearing chamber communicating with said fluid passage at said primary and secondary points; a shaft journalled in said bearing; means operatively connected to said shaft for forcing fluid through said fluid passage, a small portion of said fluid passing through said bearing; straining means at said primary point for straining said small portion of said fluid before it reaches said bearing; and means independent of said bearing and said straining means for limiting the flow of said fluid through said bearing.

3. In combination in an intermediate bearing for a deep-well turbine pump: a bearing structure providing a fluid passage and a bearing chamber; a bearing in said bearing chamber; a shaft journalled in said bearing and extending downward through an opening of said bearing structure only slightly larger in diameter than said shaft; a pump bowl secured below said bearing structure and cooperating therewith in defining an annular passage communicating between said opening and a fluid passage in said pump bowl; and an impeller rotated by said shaft and forcing well fluid upward through said fluid passages, said passages being designed to increase the pressure adjacent said annular passage to a value higher than the pressure adjacent the upper end of said bearing chamber whereby a small amount of said well fluid is strained through said annular passage and passes upward through said bearing.

50 4. A combination as defined in claim 3 including a deflector secured to said shaft and extending downward around the upper portion of said bearing structure to define an annular space through which the well fluid is discharged from said bearing chamber.

55 5. A bearing construction comprising: a bearing structure providing a fluid passage and a bearing chamber spaced therefrom and communicating at opposite ends therewith; bearing means in said bearing chamber; a shaft journalled by said bearing means; a member around said shaft and spaced close to said bearing structure to define an annular straining space opening on said fluid passage and communicating with said bearing cham-

ber, said annular passage being in the path of any fluid moving through said bearing chamber and being so narrow as to strain any abrasive particles therefrom; and means for setting up a flow of fluid from said fluid passage through said bearing means.

6. A combination as defined in claim 5 in which said member comprises an impeller bowl secured to said bearing structure.

In testimony whereof, I have hereunto set my hand at Los Angeles, California, this 4th day of November, 1929.

CERTIFICATE OF CORRECTION.

Patent No. 1,872,538.

August 16, 1932.

ARTHUR R. WEIS.

It is hereby certified that the above numbered patent was erroneously issued to "Pacific Pump Works, and George E. Bigelow", as assignees of the entire interest in said invention, whereas said patent should have been issued to the inventor said Weis, one half to Pacific Pump Works, and one fourth to George E. Bigelow, all of Huntington Park, California, as assignees, as shown by the records of assignments in this office; and that the said Letters Patent should be read with this correction therein that the same may conform to the record of the case in the Patent Office.

Signed and sealed this 22nd day of November, A. D. 1932.

(Seal)

**M. J. Moore,
Acting Commissioner of Patents.**
